(57) CLAIM

The ornamental design for a gaming desk as shown and described.

DESCRIPTION

FIG. 1 is a front perspective view of a gaming desk showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of detail 9 shown in FIG. 1;

FIG. 10 is an enlarged view of detail 10 shown in FIG. 1;

FIG. 11 is an enlarged view of detail 11 shown in FIG. 1;

FIG. 12 is an enlarged view of detail 12 shown in FIG. 2; and,

FIG. 13 is an enlarged view of detail 13 shown in FIG. 2.

The broken lines in the drawings depict portions of the gaming desk that form no part of the claimed design.

The dot-dash broken lines annotate the enlarged details in the drawings and form no part of the claimed design.
